UNITED STATES PATENT OFFICE.

CHARLES S. SPURR, OF LOS ANGELES, AND HERMAN P. RANDALL, OF PASADENA, CALIFORNIA, ASSIGNORS OF ONE-HALF TO FRANK W. FRAME, OF LOS ANGELES, CALIFORNIA.

FUEL-PACKAGE.

1,327,175.

Specification of Letters Patent.

Patented Jan. 6, 1920.

Application filed October 23, 1918. Serial No. 259,355.

To all whom it may concern:

Be it known that we, CHARLES S. SPURR and HERMAN P. RANDALL, citizens of the United States, and residing at Los Angeles and Pasadena, respectively, in the county of Los Angeles, State of California, have jointly invented new and useful Improvements in Fuel-Packages, of which the following is a specification.

10 This invention relates to fuel packages or vulcanizers and the like, and for such a vulcanizer as is shown in our co-pending application Serial No. 234,720, filed May 15, 1918. The fuel package described and claimed in 15 this present application has also been described in said co-pending application; but is not the subject matter of the claims of said co-pending application, said claims being directed to the vulcanizer itself.

20 It is an object of the present invention to provide a fuel packet, which will, in convenient, adaptable and easily handled form, provide the desired fuel charge for a vulcanizer. It is further an object of this in- 25 vention to provide a fuel package in such form as to be easily insertible in the vulcanizer; and while the present described fuel package is not at all limited to the particular type of vulcanizer described in our 30 co-pending application, yet it is particularly suitable for that use.

Heretofore it has been the practice to provide what is called a vulcanizing packet, comprising a plate with a vulcanizable rubber patch attached to one side and a body of fuel attached to the opposite side. This body of fuel has been commonly a cake of porous material, such as cardboard or straw-board which is impregnated with combustible substances. An object of our invention is the formation of a separate fuel package which is not necessarily permanently attached to a plate, and not necessarily a part of a vulcanizing package, but which is in 45 such form as to be easily placed in a vulcanizing pan; and which, withal, may be easily and cheaply manufactured, and will give efficient and positive results upon its combustion.

50 The invention will be best understood from the following detailed description of a preferred formation of fuel package; reference for this purpose being had to the accompanying drawings in which—

55 Figure 1 is a vertical longitudinal section

showing a typical form of vulcanizer with our fuel package placed therein; Fig. 2 is a perspective of our fuel package, the top being broken away for purposes of illustration; and Fig. 3 is a transverse section of our fuel package.

In the drawings we illustrate a vulcanizer apparatus which comprises essentially a base 10, a clamp yoke 11, a clamp screw 12, a spider 13, and a pan 14 carried by the spider. The tire tube or other piece of rubber wished to be vulcanized is illustrated at 15; it is placed upon the base 10 and the pan 14 is clamped down on the rubber or other vulcanizable patch 16, which is placed over the ruptured part of tire 15. Pan 14 may be made of a suitable heat conducting material, and, in the particular form of apparatus herein shown, may be made of heavy copper or steel, the pan being a permanent part of the apparatus and not discarded after each vulcanizing operation.

The bottom of the pan is preferably concave, as is shown in the drawings, so as to more or less accurately fit upon the upper convex surface of the patch 16. Such pans, and also the patches, are usually oval in plan, and the bottom of the pan is concave both longitudinally and transversely. Our fuel package is made to fit the pan.

The fuel package is shown at P and comprises a container having a bottom part 20, a top part 21, and a filling 22 of some proper fuel. This fuel is preferably a substance, or mixture of substances, capable of 90 autogenous combustion—a slow burning powder. The materials of the powder (such as sugar and saltpeter) may be mixed together in proper proportions and preferably mixed in granulated form; the loose 95 mixture being merely put into the bottom part 20 of the container and the top part 21 being put into place afterward. The container will hold a certain measure of fuel; and thus the heat value is easily regulated and made uniform for all such packages. The container itself is preferably made of some combustible substance, although we 100 preferably intend not to make it of a substance having any large heat value; being merely a container which is inflammable, and hence eliminating the necessity or bother of the user removing the cover in order to light the fuel. The user thus has a 105 fuel package in which there can be no vari- 110

ation from standard heating value, and no waste of fuel. The fuel is not exposed to the wind. The container, for instance, may be of strawboard, cardboard, or the like. 5 And it is also preferably of such a substance as will burn with very little or no flame—such a substance as will char rather than burn with a flame. Certain grades of soft and inexpensive wood pulp cardboard, 10 etc., answer well for this use; but any special and suitable substance may be used; and if necessary, for the purposes herein set forth, a cardboard or any other material of which the container is made may be impregnated either with a substance to make it more combustible where it is very hardly combustible, or may be impregnated with a substance to make it more slowly inflammable where it otherwise would burn 15 quickly or burn with flame. Ordinary materials which might burn quickly and with flame, may be impregnated with mineral substances, as with a silicate.

When it is desired to effect a vulcanizing 20 operation, the apparatus is put in the position and arrangement shown in Fig. 1, a fuel package having been placed in the pan as indicated. The fuel package is then ignited by igniting the outer container. For 25 the purposes of readily igniting the container, the top, or a portion of the top of the container, (being that part which is exposed and readily ignited with a match or the like) may be especially treated with 30 some readily oxidizable substance, (such as a solution of saltpeter in water about one to three) so that it will readily be ignited with a match. However, in the ordinary case, a cardboard, strawboard or the like, may be 35 selected which may be easily enough ignited, and which at the same time will burn with little flame. When the fuel package is consumed, the charred container, next the walls 40 of the pan, keeps the burned fuel from sticking to the pan; so that the burned matter may then be easily discarded by merely inverting the pan.

The container may preferably be formed

with its bottom 20 concave both longitudinally and transversely; or the bottom may 50 be originally formed flat and forced into the concave shape illustrated when it is placed upon the concave bottom of the pan. Preferably the top and bottom parts of the container are made to fit more or less tightly so 55 that the parts will not fall apart, without necessitating the use of any adhesive or the like; and the whole package may be made to fit the pan more or less snugly, but not necessarily tightly.

Having described a preferred form of our invention, we claim:

1. A fuel packet for vulcanizers, embodying a thin flat container of combustible material and a filling of slow burning fuel. 65
  2. A fuel packet for vulcanizers, embodying a thin flat container of combustible material and a filling of slow burning fuel in comminuted form.
  3. A fuel packet for vulcanizers, embodying a thin flat container of cardboard, and a filling of slow burning fuel.
  4. A fuel packet for vulcanizers, embodying a thin flat container of combustible material and a filling of a substance autogenously combustible. 75
  5. A fuel packet for vulcanizers, embodying a thin flat container of combustible material, and a filling of a substance slowly autogenously combustible. 80
  6. A fuel packet for vulcanizers, embodying a thin flat combustible container, and a filling of a slowly autogenously combustible substance in comminuted form.
  7. A fuel packet for vulcanizers, embodying a thin flat box-like container of slowly combustible card-board, and a filling of a slowly autogenously combustible substance in comminuted form. 85
- In witness that we claim the foregoing 90 we have hereunto subscribed our names this 15th day of October, 1918.

CHARLES S. SPURR.
HERMAN P. RANDALL.

Witness:
VIRGINIA BERINGER.
